(57) **CLAIM**

The ornamental design for a hamper as shown and described.

DESCRIPTION

FIG. 1 is a perspective top view of a hamper showing my new design;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a top sectional view of the hamper along axis 9-9 in FIG. 3;

FIG. 10 is a perspective sectional view of the hamper along axis 10-10 in FIG. 3;

FIG. 11 is an enlarged view of area 11 marked by a dash-dot-dash circle in FIG. 9;

FIG. 12 is an enlarged view of area 12 marked by a dash-dot-dash circle in FIG. 10;

FIG. 13 is a perspective view of the hamper with its lid in a closed position;

FIG. 14 is a perspective top view of the hamper fitted with an insert; and,

FIG. 15 is a perspective bottom view thereof.

Cross-line pattern, which is partially shown for ease of illustration, represents a conventional fabric material and is understood to repeat uniformly throughout the indicated area.

The dashed broken lines shown in the figures are for the purpose of illustrating portions of the hamper and form no part of the claimed design. The dashed broken lines shown in the FIGS. 14-15 are for the purpose of illustrating environmental structure and form no part of the claimed design. The dashed-dot-dashed broken lines shown in the FIGS. 9-12 indicate cutoff boundaries for the enlarged detailed portion views and form no part thereof.
